UNITED STATES PATENT OFFICE.

JOSEPH NOGUER-USALL, OF NEW HAVEN, CONNECTICUT.

HACKLE.

1,115,726.

Specification of Letters Patent.

Patented Nov. 3, 1914.

Application filed March 11, 1914. Serial No. 823,923.

To all whom it may concern:

Be it known that I, JOSEPH NOGUER-USALL, a citizen of the United States, residing at New Haven, in the county of New Haven and State of Connecticut, have invented a new and useful Improvement in Hackles; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a double 15 hackle arranged in accordance with my invention. Fig. 2 a side view of the same. Fig. 3 an end view. Fig. 4 an end view indicating three hackles arranged side by side. Fig. 5 a top or plan view of the same, 20 showing the protecting plates thereon. Fig. 6 a perspective view of one of the hackle plates detached. Fig. 7 a perspective view of one of the cleaning plates detached.

This invention relates to an improvement 25 in hackles such as are commonly employed in the preparation of hair for the manufacture of hair goods. These hackles usually consist of a series of upwardly projecting pins through which the hair is drawn 30 to untangle it and clean it.

The object of this invention is to provide a hackle which may be used first as an ordinary hackle or with a supplemental hackle which may be arranged above the primary 35 hackle or arranged in front of it, or at one side of it; and the invention consists in the construction hereinafter described and particularly recited in the claims.

In carrying out my invention, I employ 40 a primary hackle 2 comprising a plate 3 adapted to be secured to a bench in any desired manner and formed with a series of upwardly projecting pins 4 and a series of perforations 5 alternating with the pins. 45 The ends of the plates 3 are formed with vertical openings 6 adapted to receive vertically arranged posts 7. The ends are also formed with threaded openings 8 adapted to receive and support horizontal rods 9 the 50 purpose of which will hereinafter appear. The ends of the plate 3 are also provided with sockets 10 to receive the ends of coupling-pieces 11 which extend forward or rearward so that two or more hackle plates 55 may be connected together. These sockets have screws 12 by which the connecting

rods may be clamped in position. In connection with the principal hackle thus formed, I employ supplemental hackle plates 13 also provided with pins 14 and perforations 15, so that the supplemental hackle may be placed above the main hackle, the pins of one passing through the perforations in the other. The supplemental hackle will be guided on the posts 7. If desired, 60 a cleaning plate 16 having openings corresponding to the pins in the main hackle may be placed over the pins of the main hackle when that is to be used primarily for cleaning hair. These hackles are generally arranged in sets and may be used one pair in 65 advance of the other pair as indicated in Fig. 1 of the drawings, or they may be arranged side by side as shown in Fig. 4 of the drawings, according to the work to be 70 performed. A bunch of hair to be drawn is placed upon the principal hackle and if the hairs are very long they may extend into the second hackle arranged in rear of it, and the auxiliary hackles are then set 75 over the posts 7 and the needles 14 will pass into the hair which is clamped to a certain extent between the two hackles. The hair is drawn between the hackles in the usual way. I thus produce a constant pressure upon the 80 hair which is sufficient to keep it straight and tight, and this pressure continues until all the hair is drawn through the hackle. In using the double hackle, the pins 4 projecting up through the plate 13 act as a separate hackle for holding hair or for assisting 85 in untangling the ends which have been drawn between the hackles. In using a single hackle, it frequently happens that after the hair has been untangled and 90 cleaned, there is a great deal of dust and short greasy hairs which would remain between the needles at the bottom of the hackle which are very difficult to clean on account of the closely arranged needles. This 95 inconvenience may be avoided by using the plate 16 which may be lifted off when necessary, for cleaning. It will thus be seen that two sets of hackles may be employed, arranged one pair in front of the other, or 100 that the same members may be arranged side by side, or they may be divided and form four single hackles, the whole set remaining in place on the bench by the means 105 employed to secure the primary hackle.

I claim:

1. A hackle comprising a primary hackle

provided with rows of upwardly projecting pins and alternating rows of perforations, means for supporting vertically arranged posts, combined with auxiliary hackles having pins arranged in line with the perforations in the primary hackle, and perforations in line with the pins on the primary hackle.

2. A hackle comprising a primary hackle provided at its ends with openings adapted to receive horizontal rods whereby two or more hackles may be coupled together.

3. A hackle comprising a plate provided at its ends with sockets adapted to receive connecting rods, whereby two hackles may be connected together one in front of the other. ¹⁵

In testimony whereof, I have signed this specification in the presence of two subscribing witnesses.

JOSEPH NOGUER-USALL.
